STAMPING PRESS FOR PRECISION WORK

John Albert Chappuis, Neuchatel, Switzerland

Application July 22, 1943, Serial No. 495,774
In Germany February 29, 1942Sections 3 and 1, Public Law 690, August 8, 1946
Patent expires February 29, 1962

5 Claims. (Cl. 113—38)

1

The object of the invention is a press, particularly but not exclusively a stamping-press for precision work, comprising a fixed table, and a link run by connecting-rods and cranks moving between uprights surmounting the said table, the link carrying the tools.

Presses of this kind usually support the driving means for the rods on the uprights by bearings, and is connected to an eccentric with fly-wheel.

This disposition of the driving elements causes very heavy pieces to be supported by the highest parts of the press, and thus over the workman's head, which is irrational and dangerous, and besides the fact that the fly-wheel, exposed to the air, stirs up dust, this construction has other major defects.

Thus, for example, the distance of the bearings from the eccentric shaft being determined by the distance between the uprights, it is always too big and the said shaft is thrown out of shape by the effort necessary for this work. High stresses thus brought about, are transmitted to the said uprights subject to traction stress and to flexure, as they are also transmitted to the means by which the uprights are attached to the table. For this reason, it is necessary to manufacture all these pieces in exaggeratedly big sizes, without however being able to prevent them from yielding, owing to elasticity, and thus endangering the precision of work done.

The present invention does away with the above mentioned disadvantages and other disadvantages occurring in practical work. To this end the press, according to the present invention, is fitted with cranks positioned on a common and overhanging shaft which carries one on each side of a bearing, the bearing being integral with the table and located under the same. The connecting-rods cross the plane of the table to reach a link, to do which they pass through hollow uprights in slots, the extremities of the link entering the slots in order to connect with the said connecting-rods.

A simple way of constructing this press would be to make the table out of a double-T-shaped plate, the two resulting indentations and the feet of the uprights being so made that, in assembling the said pieces, the uprights containing the connecting-rods may be slid into the above mentioned indentations in the plane of the table which they complete, at least partially.

All the upper part of the press, i. e., the table, the uprights, the link, the connecting-rods and the crank-shaft, forms, in this case, a unit which is placed on a box-shaped support, and then the

2

driving organs are connected with the driving means such as the motor, fly-wheel, gears, etc.

As will be apparent from an embodiment described later as an example, the uprights have no longer any object except to guide the mobile link, the strain to which they might be put not influencing the working of the press.

The connecting-rods alone, longer than normal, are subject to a big traction stress, but it is easy to carry them out in drawn steel of such a quality that their elastic deformation needs no longer be taken into consideration.

The bearings placed between the two cranks may be made in any size desired so that a flexure of the crank shaft is rendered practically impossible.

The annexed drawing shows an embodiment of a press according to the present invention given by way of example.

Fig. 1 is a full face view.

Fig. 2 is a side view.

Fig. 3 is a plan view.

Fig. 4 shows a part of the box and of the table in cross-section.

Fig. 5 explains the method of assembling the press.

Fig. 6 concerns a modification.

Fig. 7 shows, finally, the construction of an ejector specially well adapted to the press described.

Fig. 8 is a view seen in the direction of the arrow A in Figure 7.

The press shown in Figs. 1 to 4 is composed of the two uprights 1 and 2, of the table 3 with bearing carrying plates 4 attached underneath, and of the stand, consisting of the box 5 open on its front face to allow control of the press.

The link 6, designed to effect a rising and descending movement, is run between the uprights 1 and 2 which have towards the top thereof a slot communicating their hollow interior with the exterior. A hand-wheel and a screw 7 enable control of the position of the carriage 8 designed to hold tools, and also piloted between the uprights.

Inside these uprights there are on each side of the link 6, connecting-rods 9 and 10. These two connecting-rods cross the table and enter the stand where they are connected with the crank 12 placed over-hanging on either side of a strong bearing 11, supported by bearing carrying plates 4, parallel to each other and perpendicular to the plane of the table.

Each crank has integrally connected therewith

a gear 13 but could also be so made as to be adjustable in position with regard to the gear.

A second shaft supported by bearings 14 in the lower extremity of bearing carriers 4, carries the gears 15 which drive the gears 13. The second shaft also carries a fly-wheel 16 and a connecting and disconnecting device controlled by pedal 17, not a part of the invention. The press is driven by a motor 18. A hand wheel 19 makes it possible to drive the lower shaft supported by the bearings 14 so as to effect desired adjustments when the press is fitted with a new tool.

The drawing shows, clearly, that the upper part of the press has neither fly-wheel nor driving-belt, etc., and that the connecting-rods are entirely protected by the uprights.

It is also easy to see that the said uprights of relatively simple make, are not subject to any stress other than that arising from the slipping of link 6 and of carriage 8.

The crank shaft 12 in the stand is so held in place by the bearing 11 that in no case can it be deformed. Both the crank shaft 12 and the said bearing may be made in any size.

The piece to be worked will be placed between the table 3 and the carriage 8. During the working operation, the two connecting-rods will be subjected to traction stress, with no ill effects, in view of the quality of steel chosen for the manufacture of these pieces.

The cross section according to Fig. 4 makes it possible to see, seen laterally, the outline of bearing carriers 4 and the way in which they are connected with table 3. The whole may, for instance, be made of steel plates electrically welded.

The plate constituting the table does not cover the whole of its right angle surface. The table has, on the contrary, two lateral notches or recesses 20, visible in Fig. 5, thus giving the table 3 the general appearance of a double T.

This shape is necessary to allow assembling of various constituent parts of the press.

This assembling is carried out in the following manner:

Table 3 is raised by bearing carriers 4 above the stand and is then fitted with the greater part of the various elements situated under it, that is to say, the bushings, the shafts, the toothed wheels, the cranks, etc.

Link 6 is kept in place above the table thus equipped and at a convenient height.

The two uprights 1 and 2 are then introduced and the connecting-rods 9 and 10 are suspended therein. This introduction is effected sideways so that feet 21 and 22 slide in the same sense as the plane of the table, in the recesses 20 of this latter. At the same time, it is necessary to be sure that the heads of the connecting-rods join correctly on one hand with the cranks and on the other with the link.

The feet of the uprights are so shaped as to cover entirely the recesses of the table, but said feet could be so shaped as to cover said recesses in co-operation with special covers.

The connection between table and uprights may, for instance, be effected by bolting. A transverse beam 23 (Figs. 1 to 3) ensures the rigidity of the uprights. It may also be fitted by bolting.

When the upper parts of the press are assembled, as also the principal parts of the driving mechanism, all that remains to be done is to place the whole on the stand and attach it. Assembling will be completed by arrangement of such elements as have not yet been introduced. In par-

ticular a protective iron sheet designed to hide all the driving elements visible in Fig. 1, will be added, and in such a manner that the workman seated before the press cannot in any way come into contact with the said organs.

To allow the free passage of a metal ribbon, crossing the press in the sense of arrow 24 of Fig. 1, the connecting-rods may be made according to Fig. 6. At the height where the metal ribbon 25 crosses the press, the connecting-rod is broader, with a hole 26 through which the ribbon can pass in any position of the connecting-rods. The uprights naturally have corresponding openings 27. The connecting-rod of Fig. 6 is in its upper dead point. The press could of course be provided with a device for automatic advance of the metal ribbon to be worked, it also carries a safety device not shown in the drawing.

Ejection devices, necessary for satisfactory functioning, could also be added. One of these devices shown in Fig. 7 deserves special attention.

In this figure, carriage 8 is again shown, partially in cross-section and a support 28 supposed to be part of the transverse beam 23, is likewise seen in cross-section.

Arranged transverse to this support is a rod 29 having a lower cylindrical portion 30, and an adjacent cone shaped portion 31. The cylindrical and cone shaped portions are co-axial but eccentric in relation to the rod which can slide and revolve in support 28. Screws 28' serve to lock the rod 29 in the support 28.

Opposite these elements, a roller 32 rises and falls as supported by a bell crank lever 33, pivoted at 34 upon the carriage 8. The extremity of this lever opposite to that where the roller is, presses on rod 35 for ejecting pieces retained by the tool carried by the carriage 8 upon its lower end.

The position shown is that of ejection, carriage 40 8 being near is upper dead point. Coming down, roller 32 will first roll along the lower cylindrical part 30 of rod 29, then along the cone 31, which will make lever 33 to swing in an anti-clockwise direction as shown in the drawing. Rod 35, subject for example, to the action of a spring, will rise.

At each upward movement of carriage 8, roller 32 meets the cone, swings clockwise and provokes the ejection, then finishes its course along cylinder 30.

It is possible to see that in raising or lowering rod 29, the exact moment may be regulated when ejection takes place and, from the fact that the axis of the rod 29 is eccentric with regard to the axis of the cylinder 30 and cone 31, a rotation of rod 29 in support 28 will make it possible to modify the angle through which lever 33 will swing, that is to say the amplitude of the ejection movement.

The construction described ensures a uniformly easy way to correct play since carriage 8 and link 6 are piloted in V-shaped slides. To obtain this, it suffices to slightly move the two uprights 1 and 2 toward one another. The distance between these uprights 1 and 2 is, first of all, determined, in erecting the machine, by the breadth of block 36 (Figs. 1 to 3) between the feet of said uprights. By lightly milling a lateral face of said block, the uprights positioned against it approach each other slightly. Beam 23, bolted, will not prevent this correction of play, nor will the lateral recesses 20 which will, to this end, be made larger than strictly necessary.

From the foregoing description it is clear that the present invention does away with the defects inherent in presses of this type known to date.

All driving elements are protected, being situated in enclosed spaces, whereas the part above the table is constructed in a simple manner and lends itself particularly well to clean and precise work, as especially required in the watch-making industry.

As will be clear from the foregoing, link 6, driven by the connecting rods, does not transmit its movement directly to carriage 8, but through the screw 7. This is of particular advantage from the point of view of regulating, and also ensures, perfect vertical piloting of the carriage which in this way cannot undergo any lateral strain on account of the inclined position of the connecting rods.

It should be remarked that the said connecting rods are much longer than is usual in machines of this type so that their swing from one side to another from the vertical concerns a much smaller angle than is generally the case.

What I claim is:

1. In a forming press, the combination of, a table, a pair of hollow uprights extending upwardly from said table in parallel relationship, a tool carrier member movable upwardly and downwardly having guide means thereon cooperating with guide means on said upright members to slidably support said tool carrying member between said uprights, means forming a bearing member disposed beneath said table and rigidly secured thereto, a crank shaft rotatably supported in said bearing means having an overhanging crank arm on each side of said bearing means, a link member extending between said uprights adjacent the upper ends thereof through slots provided in the upper ends of said uprights and connected to said tool carrying member for moving the same, and connecting rod means interconnecting said link and said crank arms extending through said hollow uprights for driving said link from said crank arms.

2. In a forming press, the combination of, a table, a pair of hollow uprights extending upwardly from said table in parallel relationship, a tool carrier member movable upwardly and downwardly having guide means thereon cooperating with guide means on said upright members to slidably support said tool carrying member between said uprights, means forming a bearing member disposed beneath said table and rigidly secured thereto, a crank shaft rotatably supported in said bearing means having an overhanging crank arm on each side of said bearing means, a link member extending between said uprights adjacent the upper ends thereof through slots provided in the upper ends of said uprights and connected to said tool carrying member for moving the same, and connecting rod means interconnecting said link and said crank arms extending through said hollow uprights for driving said link from said crank arms, said table being formed in the shape of a double-T-shaped plate providing indentations on opposite edges thereof that cooperate with the hollow portions of said uprights and through which said connecting rods extend for interconnecting said link and said crank arms, each of said uprights having a foot thereon that cooperates with said table to form a part thereof.

3. In a forming press, the combination of, a table, a pair of hollow uprights extending upwardly from said table in parallel relationship, a tool carrier member movable upwardly and downwardly having guide means thereon cooperating with guide means on said upright mem-

bers to slidably support said tool carrying member between said uprights, means forming a bearing member disposed beneath said table and rigidly secured thereto, a crank shaft rotatably supported in said bearing means having an overhanging crank arm on each side of said bearing means, a link member extending between said uprights adjacent the upper ends thereof through slots provided in the upper ends of said uprights and connected to said tool carrying member for moving the same, connecting rod means interconnecting said link and said crank arms extending through said hollow uprights for driving said link from said crank arms, said table being formed in the shape of a double-T-shaped plate providing indentations on opposite edges thereof that cooperate with the hollow portions of said uprights and through which said connecting rods extend for interconnecting said link and said crank arms, each of said uprights having a foot thereon that cooperates with said table to form a part thereof, and a block positioned between the feet of said uprights to establish their spaced relationship when in position in said indentations in said table.

4. In a forming press, the combination of, a table, a pair of hollow uprights extending upwardly from said table in parallel relationship, a tool carrier member movable upwardly and downwardly having guide means thereon cooperating with guide means on said upright members to slidably support said tool carrying member between said uprights, means forming a bearing member disposed beneath said table and rigidly secured thereto, a crank shaft rotatably supported in said bearing means having an overhanging crank arm on each side of said bearing means, a link member extending between said uprights adjacent the upper ends thereof through slots provided in the upper ends of said uprights and connected to said tool carrying member for moving the same, and connecting rod means interconnecting said link and said crank arms extending through said hollow uprights for driving said link from said crank arms, the body of each of said connecting rods having an opening therein aligned with the opening in the opposite connecting rod and disposed adjacent the upper surface of the table through which a work piece can pass transversely through said connecting rods, and said uprights having openings therein in alignment with the openings in said connecting rods to receive the passage of a work piece extending through said connecting rods.

5. In a forming press, the combination of, a table, a pair of hollow uprights extending upwardly from said table in parallel relationship, a tool carrier member movable upwardly and downwardly having guide means thereon cooperating with guide means on said upright members to slidably support said tool carrying member between said uprights, means forming a bearing member disposed beneath said table and rigidly secured thereto, a crank shaft rotatably supported in said bearing means having an overhanging crank arm on each side of said bearing means, a link member extending between said uprights adjacent the upper ends thereof through slots provided in the upper ends of said uprights and connected to said tool carrying member for moving the same, connecting rod means interconnecting said link and said crank arms extending through said hollow uprights for driving said link from said crank arms, an ejector mechanism carried upon said tool carrying member and hav-

ing means projecting therefrom for engaging a stationary cam means carried adjacent said uprights, said ejector mechanism consisting of a bellcrank lever pivotally mounted on said tool carrying member for rotation relatively thereto having arm means extending therefrom for engaging said cam means, and said cam means consisting of a cone shaped member rotatable about an eccentric axis to change the rotatable movement of said bellcrank lever upon reciprocation thereof as carried by said tool carrying member.
